(57) **CLAIM**

The ornamental design for a display mount, as shown and described.

DESCRIPTION

FIG. 1 is a perspective view of a display mount showing my new design in a first state;

FIG. 2 is a perspective view of second state;

FIG. 3 is a perspective view of the display mount of FIG. 1 in an alternate environment;

FIG. 4 is a front view of FIG. 1 thereof;

FIG. 5 is a rear view thereof;

FIG. 6 is a left side view thereof;

FIG. 7 is a right side view thereof;

FIG. 8 is a top plan view thereof; and,

FIG. 9 is a bottom plan view thereof.

The broken lines immediately adjacent to the shaded areas depict the bounds of the claimed design, while all other broken lines are directed to environment. The broken lines form no part of the claimed design.

1 Claim, 9 Drawing Sheets
